UNITED STATES PATENT OFFICE.

SAMUEL MILLS JACKSON, OF LOGANSPORT, INDIANA.

MACHINE FOR BUNDLING WALL-PAPER.

SPECIFICATION forming part of Letters Patent No. 362,279, dated May 3, 1887.

Application filed October 12, 1886. Serial No. 216,041. (No model.)

To all whom it may concern:

Be it known that I, SAMUEL MILLS JACKSON, of Logansport, in the county of Cass and State of Indiana, have invented certain new and useful Improvements in Machines for Bundling Wall-Paper; and I do hereby declare the following to be a full, clear, and exact description of the invention, such as will enable others skilled in the art to which it pertains to make and use it, reference being had to the accompanying drawings, which form part of this specification.

My invention relates to an improvement in machines for bundling wall-paper; and it consists in the combination of two standards which are united together, and which are provided with feet at their lower ends and with hooks at their upper ones, with pivoted levers which are rigidly connected at their lower ends by means of a cross-bar and which are provided with hooks at their upper ends, so as to close upon the stationary hooks of the standard, as will be more fully described hereinafter.

The object of my invention is to utilize one-half of the same arms which hold the paper as compressors in bundling it, and thus dispense with separate compressing devices.

Figure 1 is an end view of a machine embodying my invention, the parts being shown in one position in solid lines and in another in dotted lines. Fig. 2 is a side elevation taken at right angles to Fig. 1.

A represents two standards of any desired height, which are provided with feet B at their lower ends and the hooks C at their upper ones. The feet B are moved sufficiently far apart so as to form a solid foundation for the machine at all times. These standards A have no movement, but remain rigidly in position. These two standards are rigidly connected together by the two cross-bars D, which connect the feet together in pairs, and by the cross-bar E, which serves as a fulcrum upon which the levers turn.

The two levers G are fulcrumed upon the cross-bar E, and are united together at their lower ends by a cross-bar, H, upon which the foot is placed for the purpose of moving the

levers, and causing their upper hooked ends, 50 I, to move toward the hooks upon the standard, and thus compress the bundles of paper between them. A chain, J, is connected to one of the levers and one of the standards, for the purpose of limiting the movement of the 55 levers, and thus preventing them from being opened beyond a certain distance.

When the lower ends of the levers are drawn upward as far as they can be moved, the hooks for receiving the rolls of paper are opened to 60 their utmost width. The rolls of paper are then placed between the hooks upon the standards and the hooks upon the upper ends of the levers, and then the pressure of the foot is applied to the cross-piece which connects the lower ends of the levers together, so as to force the hooks toward the hooks upon the standards, and thus compress the rolls of paper into a bundle, so that they can be readily tied together. By using the foot to operate the levers, as here shown, both hands 65 are left free to manage the rolls of paper and tie them. The levers are made to open and close by the movements of the foot, and thus the hands are always free to attend to the rolls 70 of paper.

It will be seen that the whole machine consists of the two standards, which are provided with feet so as to support them rigidly in position, and the levers, which are pivoted upon 80 the cross-bar which connects the standards together at that point.

I am aware that saw-bucks provided with four rigid arms or holders, to which suitable devices have been connected for holding the 85 log while it is being sawed, have heretofore been used, and that compressing-machines, in which all four of the arms are pivoted together and made to compress the material, are also old; and these I disclaim. My invention 90 differs from these in having two rigid arms or holders and the other two pivoted thereto, so as to form the compressing device.

Having thus described my invention, I claim—

In a bundling-machine for wall-paper, the combination of the stationary standards A, provided with the feet B and the rigid arms

C, and which are connected together by the cross-bars B' F, with the two levers G, pivoted upon the cross-bar F, connected together at their lower ends by the cross-bar H, and having their upper ends, I, formed into hooks or arms, which act in connection with the arms C, both for holding and compressing the paper, substantially as shown.

In testimony whereof I affix my signature in presence of two witnesses.

SAMUEL MILLS JACKSON.
